PAIR OF EYE MAKE-UP SPECTACLES

Toni Holloway, 435 S. Curson, M.B.,
Los Angeles, Calif. 90036

Filed Dec. 18, 1967, Ser. No. 9,844

Term of patent 7 years

(Cl. D57—1)

FIG. 1

FIG. 3

FIG. 2

The dominant features of my design reside in the portions shown in full lines.

I claim:

The ornamental design for a pair of eye make-up spectacles, substantially as shown and described.
